UNITED STATES PATENT OFFICE

WARREN WILLIAMS FLAGG, OF ORONO, MAINE

SAFETY-RAZOR

Application filed April 11, 1932. Serial No. 604,582.

This invention relates to the class of inventions known in the art and trade as safety razors and it has more specific reference to the type of razor including a detachable 5 double-edged flexible blade adapted to be clamped between a toothed guard and arcuate backing or clamping plate.

Otherwise stated the invention has a general reference to the Gillette type of safety 10 razor and is believed to be comparatively novel and structurally different from priority devices in that it is explicitly constructed to permit the clamping or backing plate to be separated from the guard a distance sufficient 15 to permit cleansing and wiping of the blade without removing the blade or disassembling the parts of the holder.

The desired result is accomplished through 20 the use of an especially constructed holder including a tubular handle and an extensible attaching device for the clamping plate wherein said parts are constructed to permit the aforesaid result to be attained in a simple and expeditious manner.

25 In the accompanying drawings illustrating the preferred embodiment of the invention:

Figure 1 is a top plan view of the improved razor.

Figure 2 is a bottom plan view.

30 Figure 3 is a side elevational view.

Figure 4 is a longitudinal section taken approximately on the plane of the line 4—4 of Figure 3.

Figure 5 is a view like Figure 4 showing 35 the parts separated for cleaning out the blades.

Figure 6 is a perspective view of one of the parts.

Figure 7 is a section on the line 7—7 of 40 Figure 4.

Figures 8 and 9 are detail views.

Referring now to the drawings by distinguishing reference characters it will be observed that the holder comprises a tubular stem 10 which functions as a handle, and threadedly connected with one end thereof is the transversely curved toothed guard 11 of conventional design. The opposite end of the handle is internally screw threaded to 45 accommodate a plug 12, said plug, as seen 50

in Figure 9, having a central hole 13 and diametrically opposite notches or kerfs 14. These kerfs are adapted to permit passage of the ends of a retaining pin 15 carried by the intermediate portion of an extensible 55 projection rod 16. At one end of the rod is a socketed head 17, the wall of the socket being screw threaded. The opposite end of the rod is also screw threaded as at 18 to accommodate a knurled finger grip 19. This 60 arrangement is provided to permit assembling of the blade and clamping plate and projection rods 16 in the tube or handle 10.

The double edged blade is denoted by the numeral 20, the arcuate clamping or backing plate is distinguished by the numeral 21 and as usual it is formed with an elongated screw threaded retaining stud 22 adapted to pass through the central hole in the blade and tapped into the socket 17. As seen in 70 Figures 2, 3 and 8 the plate 21 is also provided with the customary equalizing pins 23 such as used on the original type of safety razor.

When the razor is assembled for shaving 75 purposes the parts occupy the position seen in Figure 4 at which time the socket 17 is retracted into the outer end portion of the tubular handle 10. Moreover at this time the retaining pin 15 has passed down through the kerfs 14 and is turned at right angles thereto as seen in Figure 7 to hold the razor blade safely in position whereby to permit the razor to be used as is customary. When 80 the user is through shaving the rod 16 is turned so as to align the pin 15 with the slot 14. Then the rod is projected to the position seen in Figure 5 and the stud 22 is backed out from the socket 17 to the point indicated 85 and the backing plate 21 angled properly to permit the blade to be washed and dried without removing the blade. Thus this projectable and retractable plunger like carrier serves to accommodate the plate 21 and blade 90 20 in a practical manner to permit the aforesaid result to be attained satisfactorily.

It is thought that the description taken 95 in connection with the drawings will enable a clear understanding of the invention to be 100

had. Therefore, a more lengthy description is thought unnecessary.

While the preferred embodiment of the invention has been shown and described, it is to be understood that minor changes coming within the field of invention claimed may be resorted to if desired.

Having thus described my invention, what I claim as new is:

- 10 A razor of the class described comprising a tubular handle member, a guard connected to the inner end of said member, a plug threaded in the outer end of said handle member and having an opening passing therethrough, and a slot intersecting the opening, a rod passing through the handle member, a pin carried by the rod and adapted to pass through the slot when the rod is in a certain position and when the rod is in another position, the pin engages the plug to hold the rod in said other position, said rod having a handle member at its outer end, and an enlarged part at its other end provided with a threaded socket, said enlarged part fitting in the inner end of the handle member when the pin is passed through the slot and the rod turned to cause the pin to engage the outer face of the plug, a second guard having a threaded stem for engaging the socket for holding a blade between itself and the first guard when the rod is moved to a position to place this enlarged part in the handle member, said enlarged part having a snug fit in the handle member.
- 25 30 35 In testimony whereof I affix my signature.
WARREN WILLIAMS FLAGG.
